George F. Stromberg, Jr., Rock Island, Ill., assignor to The Servus Rubber Company, Rock Island, Ill., a corporation of Illinois

Application March 20, 1950, Serial No. 8,637

Term of patent 7 years

(Cl. D7—4)

To all whom it may concern:

Be it known that I, George F. Stromberg, Jr., a citizen of the United States, and a resident of Rock Island, in the county of Rock Island, State of Illinois, have invented a new, original, and ornamental Design for a Rubber Shoe, of which the following is a specification, reference being had to the accompanying drawing, forming a part hereof.

Fig. 1 is an elevation of one side of a rubber shoe, showing my new design.

Fig. 2 is an elevation of the other side of the shoe shown in Fig. 1.

Fig. 3 is a front elevation of the shoe.

Fig. 4 is a rear elevation of the shoe.

Fig. 5 is a top plan view of the shoe.

I claim:

The ornamental design for a rubber shoe, as shown.

GEORGE F. STROMBERG, JR.
